EXTENSIBLE SUPPORT FOR USE IN CON-
JUNCTION WITH CABINETS AND THE
LIKE

Herman A. Sperlich, Highland Park, Mich.

Application March 22, 1935, Serial No. 12,381

20 Claims. (Cl. 312—29)

The present invention relates to protective cabinets for objects, devices or machines not continually in use. While shown and described in connection with an ironing machine cabinet, it is equally applicable to the construction of cabinets and the like for other purposes.

Among objects of the invention is the incorporation in such a cabinet of an improved movable platform so arranged that the device supported thereon is shiftable from a position within to a position entirely outside the cabinet.

Another object is a cabinet of the sort indicated in which the platform, when in its outer or extended position, is provided with improved auxiliary supporting means, while in addition such auxiliary supporting means is automatically retractable into the cabinet when closed.

Yet another object is such a cabinet construction having novel means adapted to increase the effective area of the platform, as well as stabilize the platform when in its outer position.

Another object is the provision of platform supporting mechanism enabling horizontal sliding travel of the platform and its load, incorporating swingable automatically operable auxiliary supporting means for the platform, which provides as well, check means for controlling the movement of the auxiliary supporting means, and whose parts are so constructed as to maintain a desired relationship between movements of the platform and of the auxiliary supporting means, while insuring their movement in predetermined paths.

Other objects and advantages will be apparent from the following description wherein reference is made to the accompanying drawings illustrating a preferred embodiment of my invention, and wherein similar reference numerals designate similar parts throughout the several views.

40 In the drawings:

Figure 1 is a front elevation of a cabinet constructed in accordance with the invention, parts being broken away, but indicating the doors, platform and supporting device in open and extended positions.

Figure 2 is an end elevation with parts broken away, also showing the doors open and the supported device in outer position.

50 Figure 3 is a partial view similar to Figure 2 but showing the parts in their closed and retracted position.

Figure 4 is a section taken substantially on line 4—4 of Figure 2 and looking in the direction of the arrows.

55 Figure 5 is a section taken substantially on

the line 5—5 of Figure 2 and looking in the direction of the arrows.

Figure 6 is a section taken substantially on the line 6—6 of Figure 2 and looking in the direction of the arrows.

Figure 7 is a section taken substantially on the line 7—7 of Figure 2, and looking in the direction of the arrows.

Figure 8 is a reduced and fragmentary plan view of the cabinet, showing the parts in extended 10 position.

Figure 9 is a section taken substantially on the line 9—9 of Figure 1 and looking in the direction of the arrows.

Figure 10 is a section taken substantially on 15 the line 10—10 of Figure 1 and looking in the direction of the arrows.

Figures 11, 12, 13 and 14 are sections taken substantially on lines 11—11, 12—12, 13—13, and 14—14 respectively of Figure 10, and looking in 20 the direction of the arrows.

Figures 15 and 16 are fragmentary perspective views of the track-carrying section of the cabinet and the bascule element rollable thereon, respectively.

In the drawings there is illustrated a cabinet shown as arranged to accommodate an ironing machine 20 provided with a base 21 which constitutes a movable carriage platform for the retractable support. The cabinet itself may, in the 30 construction and arrangement of its sidewalls 24, top 25 and swingable doors 26, be of more or less conventional or virtually any desired variety, the particular machine and cabinet structure shown being exemplary and subjectable to considerable 35 variation, as well be recognized. In the illustrated construction sheet metal is intended to be used for the sides, top and doors, as well as for the base, which is shown mounted on short legs 22 provided with casters 23.

The platform 21 is movable with its load from a position entirely within the cabinet, as it is shown in Figure 3 to a position entirely outside the cabinet, as it is shown in Figure 2. If the supported object is of considerable 45 weight with relation to the cabinet, as is contemplated to be the case in the illustrative embodiment here under consideration, auxiliary supporting means may also be provided for furnishing added support and bracing the assembly 50 against tipping when the carriage is in projected position. Such auxiliary supporting means may cooperate with the controlling and supporting mechanism for the carriage, and may be automatically retractable into the cabinet therewith, and 55

concealed, together with the load and all of the mechanism, when the cabinet is closed, as will also appear.

In the illustrated construction the walls of the cabinet support the entire load, which is carried upon angle irons 35 forming tracks, welded or otherwise suitably positioned near the opposite side walls in opposed parallel relation. As best shown in Figs. 2 and 11, each angle iron track element carries a laterally bent flange 35b at its rear extremity which spaces the track from the side wall and is welded to the rear wall 27 for support. The inwardly projecting horizontal track flange 35a of such angle irons are serially 10 perforated as at 35c along lines spaced from their edges to provide each track with a guide rack for a rolling pinion wheel 46, one pinion being arranged to travel along each track, in mesh with the perforations. The pinion wheels 46, 46 are 15 fast upon a cross shaft 47, and support the carriage platform 21, in cooperation with wheels 45 which travel in a slot 50 in the rolling lift or bascule extension track sections presently to be described. The cross shaft 47 will be seen to insure 20 uniform travel of the two ends of the carriage.

Additional perforations 35d in the track elements 35 similarly act as guide racks for teeth 56a of sector gear portions forming part of rolling lift or bascule extension track sections. Each extension track section is formed of a pair of plates 30 55-56 welded or otherwise secured together, one (56) carrying the teeth 56a forming the toothed guiding sector and both bearing the load by reason of the alignment of their edges. The forward extremity of each plate 55 carries an extension track flange 55a adapted when swung to horizontal position to align with and provide a continuation of the fixed track flange 35a, and to project from the cabinet in such manner as to 35 enable rolling the wheel 46 and the carriage 21 out of the cabinet thereover, the extension track sections being perforated as at 55c conformably with and to form a continuation of the rack perforations 35c of the fixed track sections, and the carriage being freely rollable from one to the other.

The curved rocker portions of the bascule extensions are approximately 90 degrees in extent, as indicated in the drawing, and preferably 50 formed as complete sector plates each having a hold-down guide roller 58 located at its approximate center and arranged to travel under an over-bent track formed by the down-turned upper end 40a of a vertical plate 40 carried between track 55 element 35 and the side wall of the cabinet. The plates 40, are flanged as at 40a and secured to the front corner posts 28 of the cabinet, as by welding, and in turn support the track irons, which are welded thereto as at 35f. The plates 40 are of 60 course so spaced from the walls as to hold the tracks in proper parallel relation, and each plate in addition to carrying the track flange 40a for the hold-down roller at its upper extremity, carries at its lower end a pivot 41 for the check link 59 by which the auxiliary leg 30 is guided, as well as the connection 42 for the counterbalance spring 60.

The perforated section of the fixed track flange 35a is somewhat cut away at its forward extremity, stopping short of the front of the cabinet to 70 provide a horizontal tongue-portion 35e serving as an abutment for a locating stop 61 carried by plate 55 of the bascule assembly to limit downward movement of the rolling lift section and 75 serve to assure alignment of the extension and

fixed track flanges. The stop bracket 61 is welded or otherwise suitably secured to the outer face of plate 55, as shown in Figure 5, 7, and 16. The guide slot 50 in the rolling-lift track section is at its inner extremity arced concentrically with the curved rocker surface, about the axis of guide roller 58. The carriage 21 is freely rollable on the wheels 45-46, the former of which are journaled on stub axles 64 carried by brackets 65 depending from the carriage 21, (Figure 4) while 10 similar but deeper hangers 48 (Figure 5) carry shaft 47 which supports the wheels 46. Also carried by hangers 48 are hold-down rollers 53 which travel beneath the track flanges 35a-55a, and so prevent any escape or disalignment of the teeth 15 of the wheels 46 with respect to the guide apertures 35c-55c.

During their travel through the arcuate portions of the guide slots the wheels 45 will be seen to actuate the rolling lift track sections, tending 20 to lift the outer extremities of the extension tracks when the carriage is moved inwardly, and vice versa. Rollers 58 serve as hold-down means for the toothed sector portions if the rolling lift tracks, preventing unmeshing or disalignment 25 thereof.

The auxiliary legs 30 are preferably pivoted to the free ends of the bascule elements to support the extension tracks when outswung to their operative horizontal positions, as by pivot 30 pins 67. The legs are guided by check links 59 pivoted to a midportion thereof. The check links will be seen to maintain the parallelism of legs 30, insuring their proper positioning beneath the extension track sections to support the same 35 when extended, and facilitating their enclosure within the cabinets when elevated to the folded position indicated in Figure 3. Springs 60 articulated to the check links 59 and to plates 40 upon which the check links are pivoted counterbalance or partially counterbalance the swinging elements to assist in raising the same.

As best indicated in Figure 5, both the toothed wheels 46 and the rolling lift track sections are thicker than their toothed portions, by reason 45 of the provision of a double thickness of sheet metal in each. The entire support is accordingly not furnished nor entire wear taken by such toothed portions, and they may be formed of sheet metal and yet provide such strength 50 and rigidity as to insure long life, although the material of which they are formed is of course optional.

The carriage 21 is shorter than the distance between the swingable sections 55, 56, providing 55 clearance for the latter, and when in extended position the carriage may be locked by drop leaf shelves 70, shown as carried by the cabinet doors 26 and also formed of sheet metal. The shelves 70 are provided with downturned flanged 60 edges 70a adapted to engage clips 72 carried upon the ends of the carriage. Such clips serve both to support the shelves in horizontal alignment with the top of the platform, and to lock the platform against inward movement. The 65 drop leaf shelves 70 may be swingably supported upon horizontal rods, as 74, projected across the inner faces of the doors 26 and through slots as 75 in the side flanges of the drop leaves, the arrangement being such, as indicated in Figure 70 9, that the leaves 70 may be held in their elevated folded position when not in use, by their slotted end portions which extend below the supporting rods beside the inner faces of the doors to lock the leaves against falling. In order 75

to drop the leaves to their positions of use it is only necessary to lift them sufficiently to allow clearance for their lower end portions. The leaves of course provide shelves for the work, and the manipulation of the work and of the machine are greatly facilitated by the fact that the machine is during use supported in a position entirely clear of the cabinet.

What I claim is:

10 1. In combination with a cabinet, track means therewithin, a carriage movable on said track means, and additional track means swingable to project from and to lie within said cabinet and forming an extension support for the carriage when projected and actuatable by the carriage.

20 2. In combination with a cabinet, track means therewithin, a carriage movable on said track means, additional track means supported by the cabinet and movable to project from or lie within the same and forming an extension support for the carriage when projected and actuatable by the carriage.

30 3. In combination with a cabinet or the like, a load-carrying carriage, track means within the cabinet upon which the carriage is movable, and a swingable track section supported by the cabinet appurtenant to an end of said track means and movable to a position in alignment therewith in which it projects from the cabinet to provide an extension of said track means upon which the carriage may be moved from the cabinet, and means connecting said swingable track section and the carriage whereby the former is actuatable by the latter.

35 4. In combination with a cabinet, a load-carrying carriage, track means within the cabinet upon which the carriage is movable, swingable extension track means supported by the cabinet appurtenant to an end of said first mentioned track means and movable from a position within to a position in which it projects from the cabinet in alignment with said first mentioned track means, to provide an extension upon which the carriage may be rolled from the cabinet, and means including a slotted portion connecting said carriage and swingable extension track means, for actuating the latter upon movement of the former.

50 5. Apparatus of the character described including a supporting element having an open front, track means carried by said supporting element, a carriage member movable upon said track means, extension track means including a rockably supported portion swingable to a position in which it forms an aligned continuation of said track means whereby the carriage member may be moved from one to another, and means providing sliding connection between said carriage and the rockably supported portion, whereby said portion may be rocked by moving the carriage member.

60 6. In combination with a supporting frame, track means mounted therein, a carriage member movable over said track means, an extension track element also carried by said frame and movable to positions in which it is projected and retracted relatively thereto, the carriage member being movable from the first mentioned track means over the extension track element and vice versa when the latter element is in projected position, and means providing driving connection between the carriage member and the extension track element for actuating said element upon movement of the carriage member.

75 7. In combination with a supporting frame,

track means mounted therein, a carriage member movable over said track means, an extension track element swingably carried by said frame and movable from a retracted position to a projected position in which it forms a substantially aligned continuation of said first mentioned track means, the carriage member being movable from the first mentioned track means over the extension track element and vice versa when the latter element is in projected position, and a cam shaped member connecting the carriage and the extension track element actuatable to swing the latter upon movement of the carriage.

8. In combination with a supporting frame, track means mounted therein, an extension track element rockably arranged upon said track means appurtenant to an end thereof and including a portion alignable with said track means when in one position to form an extension thereof, a carriage movable over said track means and the extension track element, and means for rocking said element responsively to movement of the carriage.

9. In combination with a supporting framework, track means carried thereby, a rolling-lift extension track element rockably arranged appurtenant to an end of said track means and movable from an angular retracted position to a projected aligned position in which it forms an extension thereof, a carriage movable over said track means and over the extension track element, and means connecting said carriage and element for actuating the latter responsively to movement of the former.

10. In combination with a supporting frame, track means carried thereby, a rolling-lift extension track element rockably arranged upon and appurtenant to an end of said track means and movable from an angular retracted position to a projected aligned position in which it forms an extension thereof, a carriage movable over said track means and the extension track element, and means connecting said carriage and element for actuating the latter responsively to movement of the former.

11. In combination with a supporting frame, track means carried thereby, an extension track element rockably arranged appurtenant to an end of said track means; and movable from an angular retracted position to a projected position in which it projects from the frame and forms an extension of the track means, a carriage movable in and out of the frame over said track means and the extension track element, means connecting said carriage and element for actuating the latter responsively to movement of the former, and bracing means for the extension track element also actuatable by movement of said carriage.

12. In combination with a supporting frame, track means carried thereby, a retractable extension track element swingably arranged appurtenant to an end of said track means and movable from an angular retracted position with respect thereto to a projected position in which it forms an extension of the track means, a carriage movable over said track means and the extension track element, means connecting said carriage and element for actuating the latter responsively to movement of the former, and bracing means for the extension track element also actuatable by movement of said carriage.

13. In combination with a supporting frame, track means carried thereby, an extension track

element rockably arranged appurtenant to an end of the extension track element and swingable from a retracted position to an extended position in which it projects from the frame and forms a continuation of the track means, a carriage member movable over said track means and track element and from one to the other, a slotted connection between said carriage member and extension track element arranged to move said element to extended position as the carriage member is moved on the track means toward said element, and to move said element to retracted position responsive to movement of the carriage in the opposite direction.

14. In combination with a supporting frame, track means carried thereby, an extension track element rockably arranged appurtenant to an end of the extension track element and swingable from a retracted position to an extended position in which it projects from the frame and forms a continuation of said track means, a carriage member movable over said track means and track element, means connecting the carriage member and the extension track element whereby said element is actuatable by movement of the carriage, and bracing means also actuatable by movement of the carriage and having a part connected to said extension track element for movement therewith to extended and retracted positions and arranged to brace said element when in extended position.

15. In combination with a supporting frame, track means carried thereby, an extension track element arranged appurtenant to an end of the track means and swingable from a retracted position to an extended position in which it projects from the frame and forms a continuation of said track means, a carriage member movable over said track means and track element, means providing a driving connection between the carriage member and the extension track element for moving the latter to extended position as the carriage member is moved theretoward on said track means, and for moving said element to retracted position as the carriage member is moved away from said element on said track means, and bracing means for the extension track element connected to a projectable portion thereof and movable therewith to extended and retracted positions with relation to the frame.

16. In combination with a supporting frame, track means carried thereby, a rolling-lift track element also carried by the frame and swingable from a retracted position relatively thereto to a position in which it extends therefrom to form an extension track section, toothed means for preventing disalignment of said rolling lift

track section, a carriage supported by and movable over said track means and said extension track, and driving means connecting said rolling lift track element and the carriage member for actuation of one by the other.

17. In combination with a supporting frame, track means carried thereby, a rolling-lift track element also carried by the frame and swingable from a retracted position relatively thereto to a position in which it extends therefrom to form an extension track section, a carriage supported by and movable over said track means and said extension track means, and driving means connecting said rolling lift track element and the carriage member for actuation of one by the other.

18. In combination with a cabinet having a door, track means carried by the cabinet, an extension track element also carried by the frame and movable from a retracted position with relation thereto to a position in which it projects therefrom, a carriage supported by and movable over said track means and said extension track element inwardly and outwardly of the cabinet, and means comprising an auxiliary shelf member attachable to the door and to said carriage for preventing unwanted movement of the latter and providing a support for desired objects.

19. In combination with a supporting frame, track means carried thereby, a rolling-lift track element also carried by the frame and swingable from a retracted position relatively thereto to a position in which it extends therefrom to form an extension track section, toothed means for preventing disalignment of said rolling lift track section, a carriage supported by and movable over said track means and said extension track, driving means connecting said rolling lift track element and the carriage member for actuation of one by the other, and bracing means for the rolling lift track section connected thereto and movable therewith to retracted and extended positions.

20. In combination with a cabinet having a door, track means carried by the cabinet, an extension track element also carried by the frame and movable from a retracted position with relation thereto to a position in which it projects therefrom, a carriage supported by and movable over said track means and said extension track element inwardly and outwardly of the cabinet, and means comprising a drop leaf shelf element connected to both the door and the carriage when the latter is in outwardly extended position to hold the members in desired relation and provide auxiliary shelf means.

HERMAN A. SPERLICH.
